UNITED STATES PATENT OFFICE.

RAYMOND ARCHIE SUMMERS, OF REEDS, MISSOURI.

GATE-OPERATING MECHANISM.

1,238,844.

Specification of Letters Patent.

Patented Sept. 4, 1917.

Application filed February 10, 1917. Serial No. 147,799.

To all whom it may concern:

Be it known that I, RAYMOND A. SUMMERS, a citizen of the United States, residing at Reeds, in the county of Jasper, and State 5 of Missouri, have invented certain new and useful Improvements in a Gate-Operating Mechanism; and I do hereby declare the following to be a full, clear, and exact description of the invention, such as will enable 10 others skilled in the art to which it appertains to make and use the same.

This invention relates to a gate operating mechanism and has for one of its objects the provision of a device of this character, which 15 may be readily applied to a gate of ordinary construction, so that it may be either opened or closed from points foreign to the gate.

Another object of this invention is to provide an arm detachably secured to the gate 20 and having its free end disposed at an angle thereto, to which an operating means is connected for swinging the gate either to an opened or closed position.

A further object of this invention is to 25 provide a triangular shaped plate connected to the arm and having the operating means connected thereto and a pair of chains which are connected to the latch of the gate, whereby when the operating means is operated, the 30 latch will be unfastened and the gate swung either to an opened or closed position.

A still further object of this invention is 35 the provision of a self opening gate of the above stated character, which shall be simple, durable and efficient and which may be manufactured and sold at a comparatively low cost.

With these and other objects in view as 40 will become more apparent as the description proceeds, the invention consists of certain novel features of construction, combination and arrangement of parts as will be herein-after more fully described and claimed.

For a complete understanding of my invention, reference is to be had to the following description and accompanying drawings, in which:—

Figure 1 is a side elevation of a gate operating mechanism, constructed in accordance 50 with my invention.

Fig. 2 is a top plan view of the same,

Fig. 3 is a fragmentary top plan view drawn on an enlarged scale, illustrating the operating arm and the operating means attached thereto,

Fig. 4 is a perspective view of the latch.

Referring in detail to the drawings, the numeral 1 indicates a gate post having hinged thereto a gate 2 of any ordinary construction. A post 3 is spaced from the post 1 for coöperation with the free end of the gate. A suitable keeper 4 is secured to the post 3 and is engaged by a catch consisting of a substantially U-shaped bracket having a bolt 6 slidable therein and which bolt is normally urged into engagement with the keeper 4 by a coil spring 7. A handle 6' is secured to the bolt for withdrawing it from the keeper by hand when desired. One end of the bolt 6 is bent to form an eye 8 to which is secured a cable 9 for withdrawing the bolt 6 from engagement with the cable 4 to free the gate from the post 3 whereby the gate may be swung to an opened position.

An arm 10 is secured to the hinged end 75 of the gate 2 and at the top edge thereof by U-shaped clamps 11. The arm 10 has its free end bent to extend at an angle of 45 degrees in respect to the gate 2 as illustrated at 12 of Fig. 3. A triangular shaped plate 13 80 is pivoted to the free end of the arm 10 and is provided with oppositely disposed apertures 14 to which chains 15 and 16 are connected. The free ends of the chains 15 and 16 are connected to the cable 9 after passing 85 over a pulley 17 which is journaled to one of the U-shaped clamps 11.

A supporting post 18 is located rearwardly of the gate supporting post 1 and has its upper end grooved to rotatably support an operating rod 19 which extends at right angles to the gate 2 or parallel with the road way on which the gate is adapted to close. Supporting posts 20 are spaced upon each side of the supporting post 18 and have their upper ends screwed to rotatably support the end of the operating rod 19. The rod 19 is held within the grooves of the posts 18 and 20 by suitable brackets 21. Formed on each end of the operating rod 19 are right angled 100 extensions 22, to which are pivoted hand gripping rods 23. A curved arm 24 is secured to the operating rod 19 adjacent the post 18 and has a link 25 pivoted to its free end. The link 25 extends under the triangular shaped plate 13 and has its free end bent upwardly to extend through the triangular plate as illustrated at 26 and is secured therein in any suitable manner. Secured to the post 1 adjacent the upper end is a curved 110 bracket 27 which has its other end bent to form a bearing for rotatably receiving the

operating rod 19 for further supporting the rod 19 and bracing the entire construction with the post 1.

When desiring to open the gate, the right angled extension 22 of the operating rod 19 is pulled downwardly by the rod 23, which causes the curved arm 24 to move the triangular shaped plate 13 upon its pivot so that the chains will pull upon the cable 9 releasing the bolt 6 from engagement with the keeper 4 and simultaneously the gate swings to a partially opened position and by pushing upwardly, the extensions 22 of the gate will cause the same to be swung the rest of the distance to an open position. The posts 20 are also provided with suitable keepers for engagement with the bolt 6 when the gate is swung into an opened position. To return the gate to a closed position, the right angled extensions are pulled downwardly by the rod 23, which releases the bolt 6 from engagement with the keepers carried by the posts 20 and returning the gate to a partially closed position and the extensions are then pushed upwardly and the gate swings to a closed position, as illustrated in Fig. 1. When desiring to swing the gate in a reverse direction, the arm 10 is reversed upon the gate 2 so that its bent end 12 extends at an angle of 45 degrees in the opposite direction from that shown in Fig. 3, so that upon operating the operating rod 19, the gate is swung to an opened position in the opposite direction. Secured to the post 3 are arms 5', which are adapted to engage the free end of the gate for limiting the same against swinging in one direction and which will permit the gate to swing to an open position in the opposite direction.

While I have shown and described the preferred embodiment of my invention, it will be understood that minor changes in

construction, combination and arrangement of parts may be made without departing from the spirit and scope of the invention as claimed.

What is claimed is:

1. A gate operating mechanism comprising a pair of relatively spaced posts, a gate hinged to one of said posts, a keeper secured to the other post, a latch carried by the gate normally engaging the keeper, a cable connected to the latch, an arm positioned on the gate, substantially U-shaped clamps securing the arm to the gate, said arm having its free end bent to extend at an angle with relation to the gate, a triangular shaped plate pivoted to said arm, a pulley journaled to one of the clamps and receiving the cable, chains connected to the ends of the cable and to the triangular shaped plate, and means connected to the triangular shaped plate for opening and closing the gate and simultaneously operating the latch.

2. A gate operating mechanism comprising a pair of relatively spaced posts, a gate hinged to one of said posts, a keeper secured to the other post, a latch carried by the gate and normally engaging the keeper, an arm secured to the gate, a triangular shaped plate pivoted to said arm, means for connecting the triangular shaped plate to the latch, a link connecting the triangular shaped plate, an operating rod journaled adjacent one of the posts, a curved arm secured to the operating rod and to the link, and means for operating the operating rod to open and close the gate.

In testimony whereof I affix my signature in presence of two witnesses.

RAYMOND ARCHIE SUMMERS.
